J. T. THOMPSON.
AUTOMATIC GUN.
APPLICATION FILED DEC. 2, 1920.

1,425,810.

Patented Aug. 15, 1922.

UNITED STATES PATENT OFFICE.

JOHN TALIAFERRO THOMPSON, OF NEWPORT, KENTUCKY, ASSIGNOR, BY DIRECT AND MESNE ASSIGNMENTS, TO AUTO-ORDNANCE CORPORATION, OF NEW YORK, N. Y., A CORPORATION OF NEW YORK.

AUTOMATIC GUN.

1,425,810.

Specification of Letters Patent. Patented Aug. 15, 1922.

Application filed December 2, 1920. Serial No. 427,893.

To all whom it may concern:

Be it known that I, JOHN TALIAFERRO THOMPSON, citizen of the United States of America, and resident of Newport, in the county of Campbell and State of Kentucky, have invented new and useful Improvements in Automatic Guns, of which the following is a specification.

This invention relates to a breech closure mechanism for an automatic gun and in particular to that type which provides a restraining means or a lock for the closure when in position closing the firing chamber and releasing the closure for the operation of the gun mechanism.

The principal objects of this invention are the securing of extremely rapid fire combined with a smoothness of action by the provision of means, whereby the restraining means operates in synchronism with the closure, continuous with the closure movement and in a path continuing in the same sense into and out of restraining position. These and other objects will appear from the following description:

To attain these objects the structure, chosen for their embodiment and herein-after described, has a positive means whereby the reciprocatory motion of the breech closure is converted in a motion of a restraining means transverse of the closure and continuing in the same sense for both directions of movement of the closure. More specifically, the means selected includes a rotating shaft fixedly connected to a rotating block in which the restraining means is mounted and two cams and cam grooves connecting the shaft and closure, one cam operating on the forward movement and the other on the rearward movement of the closure to rotate the shaft in one direction for both movements of the closure.

For illustration a specific embodiment is set forth in the following description and in the accompanying drawings in which:

Fig. 1 is a longitudinal section of a gun receiver showing the parts in an assembled relation.

Fig. 2 is a transverse section on the line 2-2 of Fig. 1.

Fig. 3 is a detail showing the closure and shaft connection.

Fig. 4 is a transverse section on the line 4-4 of Fig. 1 relating to the same detail.

In the receiver 1 is mounted for reciprocation, a breech closure or bolt 2 and a recoil spring 3 for urging the closure into its forward position. Made integral with the closure is an extension 4 with opening 5 extending through it for the passage of 60 a shaft 6. At one end of the shaft 6 is a block 7 of cylindrical shape, and on either side of the block are journals 8 and 9, seated in bearings 10 and 11 which are formed as part of their receiver. The other end 12 of the shaft is journaled in a bearing 13, threaded in the receiver. To take up the end thrust on the shaft, collars 14 and 15 are provided, the latter being removable to permit assemblage. Ball bearing between 70 these collars and their seats in bearings 9 and 10 minimize friction.

In the opening 5 are secured two sleeves 16 and 17 (Figs. 1 and 3) through which the shaft passes. On one end of the sleeves 75 are ratchet teeth 18 which cooperate with ratchet teeth 19 similarly placed on the end of sleeves 20 and 21 in axial alignment with the sleeves 16 and 17. An inwardly projecting cam 22 on the sleeve 20 fits in a 80 helical groove 23 on the shaft, and a similar cam 24 on the sleeve 21 fits in a like helical groove 25, but of opposite pitch, in the shaft 6. Duplicates of these cams and grooves, diametrically opposite, are also provided. A 85 compression spring 26 holds the ratchet teeth in yielding connection.

The block rotates in a cylindrical seat 30 formed in the receiver. In the block are provided slots 27 (Fig. 2) which, as 90 shown, are three in number, and in the slots are slidably fitted lugs 28. Compression springs 29 tend to force these lugs outwardly from the block. In the closure 2 is formed a slot 31 with which the lugs are 95 adapted to cooperate. This slot 31 has a cam face 32 and the lugs have a similar cam face 33. These cam faces may have an inclination which embodies the principle described in the Blish Patent 1,131,319, 100 March 9, 1915 for depressing the lug into its slot when the pressure in the closure is reduced to a desired amount as set forth in that patent. The pitch of the helical

grooves in the shaft is such that the shaft rotates a distance sufficient to move a lug from its initial into operative position during the reciprocation of the bolt. Consequently, as there are three lugs, the pitch selected is that which moves a lug one-sixth of a revolution during a single movement of the closure.

As shown in Fig. 2, the lugs 28 are substantially twice as wide as the closure 2. The receiver is formed with guides 33' and shoulders 34 forming a space into which the lug is adapted to fit. The area of contact of the shoulders 34 and the lug 28 is substantially the same as that of the closure and the lug. In each lug cam face is formed a slot 41 which permits the lug to move past the end of a firing pin 40 lying in a bore 42 of the closure. The inclination of this slot gives the pin a blow in the forward direction as the lug moves upwardly.

On the extension 4 are provided notches 35 for co-operation with a sear 36 for holding the closure in its rearward position. The sear and its operation forms no part of the present invention and its disclosure is therefore omitted.

For assembling purposes, the receiver is made in two parts 37 and 38 separable along the line of 39 as shown. The upper halves of the bearings 10 and 11 are integral with the part 37 while the lower halves are integral with the part 38. The closure 2 and the shaft 6 and associated parts are placed in the part 37, the closure being in retracted position. The closure is then moved forward and the spring 3 inserted. The lower part 38 of the receiver with the trigger mechanism is then put in place and secured.

In operation, the closure 2, being in retracted position, is released from the sear. The closure moves forward, rotating the shaft 6 one-sixth of a revolution, so that a lug 28 rotates into alignment with the vertical plane of the closure as the slot 31 comes into position for the lug to be sprung into it by its spring 29. The sliding movement of the lug at the same time operates the firing pin and the recoil due to the firing causes the cam face on the closure to press on that on the lug. If the Blish angle is used, a depression of the lug occurs when the recoil pressure has been reduced to a definite amount. The depression of the lug into its slot out of the path of the closure permits the closure to continue its rearward movement, and this rearward movement causes a rotation of the lug through another sixth of a revolution into contact with the walls of the seat 30. This movement of the lug is in the same angular direction as its previous entry. The next forward movement of the closure repeats this action turning the lugs through another sixth of a rev-

olution to align a second lug with the closure. In continuous firing where the motion of the closure is practically continuous the block carrying the lugs rotates in one direction. This continuous rotation, in conjunction with the movement of the closure and in synchronism with it, gives a smoothness of action and permits a rapidity of fire not heretofore attained, without loss in accuracy.

In a copending application Serial No. 427,892 filed on even date herewith, I have illustrated another species of the invention here presented. Trigger and magazine mechanism for use with the structure of this application are shown in copending application Serial No. 427,891 filed on even date herewith which discloses and claims the generic invention.

I claim:

1. A gun comprising a breech closure movable into and out of firing position, means separate from the closure for restraining the closure in firing position, and mechanism positively connecting said means with said closure and actuated kinematically by said closure to move said means into and out of restraining position synchronously with the movement of the closure.

2. A gun comprising a reciprocatable breech closure, rotary means for restraining said closure in firing position, and mechanism actuated by the closure for positively rotating said restraining means in one continuous path into and out of restraining position in synchronism with the closure.

3. A gun comprising a breech closure movable into and out of firing position, means separate from the closure for restraining the closure in firing position, and mechanism positively connecting said means with said closure to move said means, in the same sense, into and out of restraining position synchronously with the movement of the closure.

4. A gun comprising a reciprocatable breech closure, rotary means for restraining said closure in firing position, and mechanism actuated by the closure for positively rotating said closure, in the same angular direction, into and out of restraining position in synchronism with the closure.

5. A gun comprising a breech closure movable into and out of firing position, means movable into and out of position to restrain said closure in firing position, and mechanism kinematically connecting said means with said closure so that the restraining means moves at a rate bearing the same proportion to the rate of movement of the closure at every instant.

6. A gun comprising a breech closure reciprocatable into and out of firing position, means for restraining said closure in firing position, said means having a rotatable por-

tion, and mechanism kinematically connecting said means with said closure so that said portion rotates at a rate bearing a constant proportion to the rate of movement of 5 the closure.

7. A gun comprising a breech closure movable into and out of firing position, means movable in the same sense into and out of position to restrain said closure in 10 firing position; and mechanism kinematically connecting said means with said closure so that the restraining means moves at a rate bearing the same proportion to the rate of movement of the closure at every instant.

15 8. A gun comprising a breech closure reciprocatable into and out of firing position, means for restraining said closure in firing position, said means having a rotatable portion rotatable in the same sense into and out 20 of restraining position, and mechanism kinematically connecting said means with said closure so that said portion rotates at a rate bearing a constant proportion to the rate of movement of the closure.

25 9. A gun having a breech closure movable into and out of firing position, and means for restraining the closure in firing position, said means comprising a carrier movable adjacent the path of the breech closure and 30 at an angle thereto, and a spring-pressed lug movably mounted on the carrier to move behind an abutment on the breech closure in a certain position of the carrier.

35 10. A gun having a breech closure movable into and out of firing position, and means for restraining the closure in firing position, said means comprising a carrier movable adjacent the path of the breech closure, and a spring-pressed lug movably 40 mounted on the carrier to move behind an abutment on the breech closure in a certain position of the carrier, said lug having a closure-engaging surface inclined to the path of the breech closure at such angle 45 that the lug is automatically forced out of the path of the closure by the breech pressure acting through the closure after the breech pressure has decreased to a safe value.

11. A gun comprising a reciprocable breech closure, means rotatable in one direction for restraining said closure in firing position, and mechanism actuated by the closure for positively rotating said restraining means into and out of restraining position in synchronism with the closure. 50 55

12. An operating means for a restraining means for a breech closure slidable in a receiver of a gun, consisting of a shaft rotatably mounted in said receiver and associated with the restraining means, a member carried by the closure, a ratchet connection between said member and closure, and means for rotating the shaft by the member, said means including a cam and groove, whereby said restraining means is 60 65 moved substantially throughout the period of movement of the closure.

13. An operating means for a restraining means for a breech closure slidable in a receiver of a gun, consisting of a shaft rotatably mounted in said receiver and associated with the restraining means, a plurality of members carried by the closure, ratchet connections between said members and the closure, and means for operating the 70 75 shaft by the members, said means including cams and grooves.

14. An operating means for a restraining means for a breech closure reciprocable in a receiver of a gun, consisting of two members 80 carried by the closure and rotatable therein, ratchet connections between said members and the closure, the ratchet connection for one member being opposite in engagement to that of the other member for 85 locking said members alternately to the closure upon each reverse movement of the closure, a shaft rotatably mounted in said receiver and associated with said members and the restraining means, said shaft and 90 members having cooperating cams and grooves to rotate said shaft by the member locked to the closure.

Signed by me at New Canaan, Connecticut, this 30th day of November 1920.

JOHN TALIAFERRO THOMPSON.
